(57) **CLAIM**

The ornamental design for a pair of headphones, as shown and described.

DESCRIPTION

FIG. 1 is a back perspective view of a left headphone of a pair of headphones showing my new design;

FIG. 2 is a front perspective view of the headphone of FIG. 1;

FIG. 3 is a back elevational view of the headphone of FIG. 1;

FIG. 4 is a front elevational view of the headphone of FIG. 1;

FIG. 5 is a right side elevational view of the headphone of FIG. 1;

FIG. 6 is a left side elevational view of the headphone of FIG. 1;

FIG. 7 is a top plan view of the headphone of FIG. 1;

FIG. 8 is a bottom plan view of the headphone of FIG. 1;

FIG. 9 is a back perspective view of a right headphone of a pair of headphones of my new design;

FIG. 10 is a front perspective view of the headphone of FIG. 9;

FIG. 11 is a back elevational view of the headphone of FIG. 9;

FIG. 12 is a front elevational view of the headphone of FIG. 9;

FIG. 13 is a right side elevational view of the headphone of FIG. 9;

FIG. 14 is a left side elevational view of the headphone of FIG. 9;

FIG. 15 is a top plan view of the headphone of FIG. 9; and,

FIG. 16 is a bottom plan view of the headphone of FIG. 9. The broken line showings and unshaded areas depict environment that forms no part of the claimed design.

1 Claim, 16 Drawing Sheets
